UNITED STATES PATENT OFFICE.

EMMA COLD REYNOLDS, OF PHILADELPHIA, PENNSYLVANIA.

DESIGN FOR AN EMBLEM.

51,510.

Specification for Design.

Patented Nov. 20, 1917.

Application filed October 4, 1917. Serial No. 194,812. Term of patent 3½ years.

To all whom it may concern:

Be it known that I, EMMA C. REYNOLDS, a citizen of the United States, residing at Philadelphia, in the county of Philadelphia and State of Pennsylvania, have invented a new, original, and ornamental Design for an Emblem, of which the following is a specification, reference being had to the accompanying drawing, forming part thereof.

The figure is a front elevation of an emblem, showing my new design.

I claim:—

The ornamental design for an emblem, as shown.

EMMA COLD REYNOLDS.

Witnesses:

MAX SCHERME,

DAVID R. REYNOLDS.
